UNITED STATES PATENT OFFICE.

CLARENCE E. ROGERS, OF HARPER, KANSAS.

FOLDING CRATE OR COOP.

SPECIFICATION forming part of Letters Patent No. 634,031, dated October 3, 1899.

Application filed March 23, 1899; Serial No. 710,271. (No model.)

To all whom it may concern:

Be it known that I, CLARENCE E. ROGERS, a citizen of the United States, residing at Harper, in the county of Harper and State of Kansas, have invented a certain new and useful 5 Folding Crate or Coop, of which the following is a specification.

My invention relates to crates for shipping eggs, vegetables, &c., and to coops for shipping poultry.

One of the greatest drawbacks to farmers, truckers, and poultry-raisers has been the expense due to the shipment of their produce—such, for instance, as the first cost of the 15 crates or coops and the return freight on them when empty. Owing to the great saving in freight on return crates and coops by making them to fold or knockdown many efforts have been made to furnish a crate cheap as to first 20 cost and strong and durable which will fold compactly and easily; but none of such efforts have been attended with entire success.

It is the object of my invention to provide a folding coop or crate which will as near as 25 may be overcome all objections to crates now in use; and with this object in view my invention consists in a folding coop or crate embodying the improved construction, arrangement, and combination of parts hereinafter 30 fully described and afterward specifically pointed out in the claim.

In order to enable others skilled in the art to which my invention most nearly appertains to make and use the same, I will now proceed 35 to describe its construction and operation, having reference to the accompanying drawings, forming part hereof, in which—

Figure 1 is a view in perspective of a crate or coop constructed in accordance with my invention set up and closed, as when shipped full. Fig. 2 is a top plan view of the bottom with sides and ends hinged thereto, one side being folded on top of the bottom and the other lying out in line therewith and one end 45 lying out in line with the bottom and the other folded under it, the latter being indicated in dotted lines. Fig. 3 is a perspective view illustrating a removable partition, and Fig. 4 is a transverse vertical section through the 50 crate or coop folded for return shipment.

Like letters of reference mark the same parts in all the figures of the drawings.

Referring to the drawings by letters, A indicates the bottom, preferably made of sheet-iron, although it may be made of wood or other material; having transverse cleats B on its inner side.

C D indicate the sides, in this instance shown as composed of slats, although I contemplate making them solid, of metal or wood or of woven wire-cloth or other suitable materials, such materials being also applicable in the manufacture of the ends, top, and partitions, to be hereinafter described. The sides are stiffened and strengthened by transverse cleats C' C² and D' D², secured upon the outside, and are attached to the bottom by hinges E, secured to the inside of the bottom and sides, in line with the cleats, so that said sides may be folded down on the upper face of the 70 bottom or stood up at right angles thereto, as may be desired.

F and G indicate the ends, which, like the sides, are strengthened by transverse cleats F' G', the cleats, however, being placed inside instead of outside, and these ends are attached to the bottom by means of hinges H, secured on the outside of the ends and the under face of the bottom, the result of this arrangement of the hinges being that 80 the ends can be folded flat against the under face of the bottom or swung around to a position above and at right angles to the bottom, but cannot be swung any farther inward.

I indicates the top or cover, which is constructed with depending flanges J all around, so as to overlap the sides and ends when in their upright positions, as shown in Fig. 1, the ends in this position standing between the sides and preventing them from being 90 folded or falling inward and the dependent flanges of the top preventing either sides or ends from falling outward.

K indicates hooks on the flanges of the top or cover and engaging eyes or staples on the 95 sides, whereby the cover is firmly held in position.

L indicates a partition which may or may not be used and which is provided with pins M, projecting from its lower edge to engage holes 100 N in the bottom, and with parallel cleats O, projecting from its upper edge to engage a vertical slat or cleat P on the inside of the cover.

When emptied and to be returned or stored, the crate or coop is folded, as shown in Fig. 4, in which position the sides are folded down on the upper face of the bottom, the ends folded upon the under face of the bottom, the partition (when one is used) laid on the under face of the bottom between the ends, and the top placed over the folded ends and partition, the sides being secured by a hook Q and the top by the hooks K, suitable eyes being provided for engaging said hooks.

The advantages attending the use of my invention are many and obvious. The whole structure is held stiff and rigid while in use, so that it will not be injured by piling ordinary boxes or packages upon it, and it can be readily folded into a compact bundle for return shipment. It may be cheaply made and be strong, light, and easily portable.

Having thus fully described my invention, what I claim as new, and desire to secure by Letters Patent of the United States, is—

In a folding crate or coop, the combination with the bottom having a transverse series of holes, folding sides and ends, a cover provided with depending edge flanges to encompass the upper edges of the sides and ends when standing and with inner transverse, vertically-arranged cleat or slat in the same vertical plane as the holes in the bottom, and a removable partition provided with pins to enter the holes in the bottom and cleats to embrace the transverse vertical cleat of the cover, substantially as described.

CLARENCE E. ROGERS.
